(57) CLAIM

The ornamental design for a sofa as shown and described.

DESCRIPTION

FIG. 1 is a top perspective view of a sofa showing our new design in a first configuration of use;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top perspective view of the sofa of FIG. 1, shown with environmental subject matter.

The broken lines in the drawings depict environmental subject matter, specifically an ottoman, and forms no part of the claimed design.

1 Claim, 8 Drawing Sheets
